US00D453929S

(12) **United States Design Patent** (10) Patent No.: **US D453,929 S**
 Gartrell et al. (45) Date of Patent: ** Feb. 26, 2002

(54) **POWER BUTTON AREA FOR A HANDSET**

(75) Inventors: **Andrew Gartrell; Dimitre Mehandjisky**, both of Calabasas; **Kelley Ann Chao-Fei Ching Lee**, Pasadena, all of CA (US)

(73) Assignee: **Nokia Mobile Phones Ltd.**, Espoo (FI)

(**) Term: **14 Years**

(21) Appl. No.: **29/126,962**

(22) Filed: **Jul. 26, 2000**

(51) LOC (7) Cl. **14-03**

(52) U.S. Cl. **D14/248**

(58) Field of Search D14/137, 138, D14/218, 147-148, 247-248, 144, 242, 341-347, 191, 188, 192, 197, 198; 379/434, 433.01, 433.04, 419, 420, 433.06, 433.07, 440, 428.01, 433, 455/550-575, 90, 347, 350, 351; D13/168; D18/2, 7
